UNITED STATES PATENT OFFICE.

ADONIRAM J. COLLAR, OF YREKA, CALIFORNIA.

HYDRAULIC ENGINE.

SPECIFICATION forming part of Letters Patent No. 560,394, dated May 19, 1896.

Application filed September 6, 1895. Serial No. 561,684. (No model.)

To all whom it may concern.

Be it known that I, ADONIRAM J. COLLAR, a citizen of the United States, residing in Yreka, county of Siskiyou, State of California, have invented an Improvement in Hydraulic Engines; and I hereby declare the following to be a full, clear, and exact description of the same.

My invention relates to a hydraulic engine 10 which is adapted to be actuated by liquid under pressure.

It consists in certain details of construction which will be more fully explained by reference to the accompanying drawings, in 15 which—

Figure 1 is a diagrammatic view of my cylinders in sections. Fig. 2 is an outside view showing their relative positions. Fig. 3 is a section through one of the cylinders, the piston 20 ton being shown in half-section. Fig. 4 is a vertical section through one of the sliding blocks on line *y y* of Fig. 6. Fig. 5 is an edge view of the same. Fig. 6 is a top view of the same.

25 The object of my invention is to provide an apparatus in which a liquid under pressure is admitted successively to connected cylinders and a mechanism whereby the pressure of the liquid acts at the proper time 30 upon pistons reciprocating within said cylinders, the piston-rods being connected with cranks upon the shaft, so as to convert the alternate reciprocating motions of the pistons into a continuous rotary motion of the 35 crank-shaft.

In the present construction of my apparatus I have shown four cylinders A B C D, situated in pairs, one above the other, each cylinder having a piston E reciprocating 40 within it; but the relative arrangement and position of the cylinders may be changed without essentially changing the construction and operation. Piston-rods F extend from these pistons through the cylinder-heads 45 and are connected with slides G, which travel in suitable guides H. These slides have transverse slots in them which form guides for blocks I, within which turn the crank-pins J, projecting, as shown in the present 50 case, from crank-disks J', which are fixed upon the main driving-shaft K. Upon this shaft may be fixed pulleys, gears, or other

means for communicating power, and the movement of the pistons is transmitted through these connections to transmit power. 55 The cylinders are made with the central portion of smaller diameter than the ends. Within the cylinders sleeves or linings L are fitted in the smaller central portion and extend to the ends of the cylinder. These 60 lining-sleeves have slots or channels M made in that portion which lies within the ends of the cylinders, so that water which enters these ends may pass through the slots or channels into the interior of the lining-cylinders from one end and out through the opposite end.

The pistons E are provided with packing-rings N, which fit within the lining-sleeve L and form close joints when the pistons are 70 moving in the unperforated central portion of the linings. The pistons have cages projecting from them, as shown at O, these cages being closed at one end, and within these cages valves P are adapted to reciprocate. 75 The pistons themselves are hollow and have seats formed in them, as shown at Q, against which the valves fit when closed upon the pistons, thus temporarily making a solid piston. When the valves are moved in the other direction, they fit in the closed heads O of the cages and leave openings between the longitudinal arms of the cages, through which water may pass freely into and through the linings and pistons. The valves have single 80 stems R, projecting from one end through the ends of the cages, and parallel double guide-rods R', projecting from the opposite ends, on each side of the piston-rods. The uppermost cylinder upon one side is connected by a pipe 90 S with the source of supply, so that water under pressure is admitted through this pipe into one end of the cylinder surrounding the lining L, and it is admitted through the slots M into the interior of the lining. Whenever 95 the piston is at that end of the cylinder, with its valve open, water flowing into the lining can also pass through the side bars of the cage and through the open central portion of the piston, flowing to the opposite end of the 100 cylinder. At this point it can pass out through the corresponding slots M into the enlarged chamber at that end of the cylinder and will pass through a connecting-passage S' to the

cylinder below, which is constructed similarly to that above with the exception that the arrangement of the valve with relation to the piston is reversed, and if this piston is at the 5 end of the cylinder through which water enters it may in the same manner pass through the piston to the opposite end. From the opposite end of this lower cylinder a pipe S^2 extends diagonally to the front end of the other 10 upper cylinder, so as to deliver water into it in the same manner as water is delivered into the cylinder B, and in like manner the opposite end of this upper and lower cylinder C and D is connected by a pipe similar to the pipe S' . 15 A discharge pipe or passage S^4 connects with the opposite end of the final cylinder. The crank-pins are fixed with relation to each other and the shaft to stand at right angles, so that when one crank is on a dead-center 20 the other will be in position to exercise its greatest power.

The central unslotted portion of the cylinders and the linings in which the piston fits and in which the water-pressure can act upon 25 the pistons when their valves are closed is approximately equal in length to one side of a square inscribed within the circle described by the cranks, less the width of the packing-rings, so that the pistons are exterior to this 30 closed portion while the cranks are making one-quarter of a revolution, half of which quarter is upon each side of the dead-center. As soon as the crank has moved one-eighth of a revolution from the dead-center the piston 35 will have entered the central unslotted portion of the lining, and the valve being closed the water exercises a pressure upon the piston while it is passing through this portion of the lining. As soon as the piston has passed out 40 of this central portion the water is at liberty to escape through the sides of the cage behind the valve and through the slots M in the lining into the opposite enlarged end of the cylinder.

45 The operation will be as follows: When the upper piston moves toward the rear end of its cylinder, the valve P lying within the closed end of the cage and the guide-rod R projecting through this end, the end of this 50 rod will strike the end of the cylinder or a stop fixed for that purpose, and the valve will then be forced by the further movement of the piston against the seat Q of the piston, thus closing the central opening of the piston 55 and preparing it to receive the pressure of water. As the positions of the pistons in the various cylinders are such that some one piston will be receiving the pressure of water this upper piston, just described, will commence 60 its return stroke, the water meantime flowing through the bars of the cage in front of the piston until the piston itself is within the unslotted central portion of the lining L, when it immediately cuts off this water flow, and as the 65 valve P is closed against the seat in the piston the pressure of the water acts upon this piston to carry it through the unslotted central

portion of the lining. This stroke occupies a distance equal to one side of the square previously described as being formed within 70 the circle described by the crank, and the power is thus applied to the crank during the most effective portion of its revolution. As soon as the piston passes out at the opposite end of the closed central lining the water 75 which has followed it to this point escapes through the open sides of the rear portion of the cage and thence through the slots M in the lining into the surrounding enlarged chamber of the cylinder, from which it passes through the passage S' into the cylinder below. As the piston in this cylinder is moving parallel with and simultaneously with the piston just described in the upper cylinder it is not receiving pressure up to this time. 80 This piston stands in a reversed position from that in the upper cylinder, and its valve being open during this portion of the movement the water which passes through S' flows into and through the lower cylinder and thence 85 into the upper cylinder upon the opposite side, the piston of which at this time has reached the point where the pressure will act upon it in the same manner as just described for the first upper piston. This continues the movement of the first-described 90 upper and lower pistons, and the guide-rods R' of the upper piston-valve, extending through the end of the cage from the valve-rod, will come in contact with the cylinder-head upon each side of the piston-rod, thus 95 stopping the valve, while the piston continues its movement until the valve has been forced into the end of the cage which it occupied at the beginning of this description. Spring-arms P' are fixed upon each side of the cage 100 and press against the valve, so as to prevent its being moved from this position without the actual pressure applied by the rod R, and the valve is in like manner held upon its seat 105 in the piston by similar springs, from which it is disengaged when the rods R' strike the opposite end of the cylinder. The return of the valve P into the head of the cage O leaves 110 the central portion of the piston open, and as the sides of the cage are also open water can flow freely through the piston while the latter returns to the commencement of its stroke. The same movement of the lower piston 115 simultaneously with the movement which opens the valve P of the upper cylinder acts to close the corresponding valve against the lower piston, and as these two pistons commence their 120 return movement the water passes freely 125 through the upper piston, and as soon as the lower piston enters the central unperforated portion of its cylinder and sleeve the pressure of the water commences to act upon it and thus forces it back, continuing the rotation 130 of the crank upon the opposite side of the square previously referred to. The second upper piston, which was acting until the first 135 upper and lower pistons had reached the front

end of the stroke, will now have reached the end of its cylinder, and its valve will have been opened so as to allow this piston to return to the opposite end of its stroke, and 5 the lower piston upon that side will have its valve closed, so that as soon as the lower piston on the first-described side has completed its active stroke the second lower piston will be closed in readiness to receive the pressure 10 of the water, which will be flowing through the second upper piston and through the connecting-passage into the second lower cylinder. It will thus be seen that the two upper pistons are acted upon from the rear toward 15 the front end, thus applying the power to rotate their respective cranks the first part of their revolution, and the two lower pistons act in the opposite direction, or when they are moving toward the rear ends of the cylinders, 20 and as these cylinders act intermediately and alternately it will be seen that one or the other of the pistons is constantly at work, so that the power is applied continuously during the entire rotation of the crank and shaft 25 through either one or the other of the pistons.

In order to reduce the friction of the transversely-moving slide I, which is connected with the crank-pin, I have shown channels made around its periphery, and within these 30 channels are loosely fitted balls I'. There are two of these channels extending parallel and diagonally from one side to the other of the sliding block I and so disposed that the pressure is constantly central upon the balls, 35 while the balls are free to travel continuously around within the chambers, so as not to be forced against each other and produce undue friction.

Having thus described my invention, what 40 I claim as new, and desire to secure by Letters Patent, is—

1. A hydraulic engine consisting of cylinders arranged in pairs, one of each pair receiving water under pressure at one end and 45 delivering it into its mate at the opposite end, a diagonal pipe by which water is delivered from the second cylinder of the first pair to the first cylinder of the second pair, a connection between the opposite ends of the second pair, open pistons reciprocating within 50 said cylinders connecting with cranks upon a common crank-shaft and valves closing the pistons so that the pressure of the water is alternately applied to the various pistons.

55 2. A hydraulic engine consisting of the combination of two pairs of cylinders, one cylinder of each pair receiving water under pressure at one end and delivering it into its mate at the opposite end, a connection whereby water is delivered from the second cylinder of one pair to the first cylinder of the other pair, open pistons reciprocating in the cylinders, 60 slides reciprocating in guides and connected with the piston-rods so that each pair of pis-

tons move in unison, transverse slots made 65 in said slides, and other slides connected with the crank-pins movable in said transverse slots whereby power applied to either piston of a pair acts through the common connecting-slide upon the single crank-pin. 70

3. A hydraulic engine consisting of parallel cylinders arranged in pairs with pistons reciprocating therein, piston-rods connecting the pistons of each pair with a slide movable in guides parallel with the line of travel of the piston-rod, transverse slides movable in channels across the main slides and connected with a common crank-pin whereby the power applied to either piston of a pair is transmitted to the single crank-pin, mechanism connected with the pistons whereby pressure of water is applied to move one piston of a pair 75 in one direction and the other piston in the opposite direction. 80

4. A hydraulic engine consisting of parallel cylinders arranged in pairs with pistons reciprocating therein, piston-rods by which each pair of pistons is connected with a common slide and crank-pin, cylindrical linings extending from end to end of the cylinders, 90 within which linings the pistons are fitted with packing-rings, chambers formed at the ends of the cylinder of larger diameter than the central portion of the linings, with slots or channels through which water can pass 95 into and out of the linings, valves movable so as to leave central openings through the pistons when the latter are moving against the flow of water and closable against the pistons so that the pressure of the water may be applied thereto when the pistons move within the unperforated portions of the cylinders. 100

5. In a hydraulic engine, cylinders having a central portion with a lining adapted to fit therein, enlarged end sections through which 105 the lining extends with slots or channels whereby communication is had from the interior to the exterior of the lining within these enlarged ends, a supply-pipe through which water is admitted to one end of the 110 cylinder exterior to the lining, and a pipe by which it is discharged from the opposite end of the cylinder, a cage connected with the piston a valve movable within the cage so as to close against the central open portion of the 115 piston when the latter is moving in the direction of the water flow, and be moved into the head of the cage so as to leave free passage through the piston when the latter is moving in the opposite direction. 120

6. In a hydraulic engine, the combination, of a plurality of cylinders arranged in pairs, one cylinder of each pair receiving water under pressure at one end and delivering it into its mate at the opposite end, a connection 125 whereby water is delivered from the second cylinder of one pair to the first cylinder of the other pair, a connection between the op-

posite ends of the second pair, pistons and devices transmitting power to a common rotary shaft, and mechanism whereby the flow of the current is interrupted within the various cylinders in such order that its force will be applied to move the various pistons and transmit their powers successively to the shaft.

In witness whereof I have hereunto set my hand.
